UNITED STATES PATENT OFFICE.

JAMES K. DELANO, JR., OF LOUISVILLE, KENTUCKY.

OVERLOAD-SWITCH.

1,261,777.

Specification of Letters Patent. Patented Apr. 9, 1918.

Application filed March 8, 1915. Serial No. 13,047.

To all whom it may concern:

Be it known that I, JAMES K. DELANO, Jr., a citizen of the United States, residing at Louisville, in the county of Jefferson and State of Kentucky, have invented certain new Improvements in Overload-Switches; and I do hereby declare the following to be a full, clear, and exact description of the invention, such as will enable others skilled in the art to which it appertains to make and use the same.

This invention relates to an over-load switch for use on low voltage work as supplied by storage battery current and particularly in connection with lighting circuits for automobiles.

One of the objects of the invention is to provide an over-load switch simple and economical in construction and designed to occupy a minimum amount of space.

A further object of invention is to provide an over-load switch placed in a circuit and adapted to utilize an excessive current passing therethrough to magnetize a core for the purpose of attracting an armature to displace a contact member and thereby break the circuit.

With these and other objects in view the invention consists in certain novel features of construction and arrangement of parts hereinafter fully described and illustrated in the accompanying drawing, it being understood that various changes in the form, proportions and minor details of the device may be made without departing from the spirit of the invention.

In the accompanying drawing Figure 1 represents a longitudinal sectional view through the device with the switch in closed position. Fig. 2 represents a similar view showing the device connected up with a battery and a series of lamps with the switch in open position.

Similar numerals of reference are employed to indicate corresponding parts throughout the several figures of the drawing.

Referring to the drawings by numerals, 10 represents a casing closed at one end by an insulating block 11 and at the other end by a circular flange 12 carrying a core 13 formed of magnetic material and extending into the casing 10. The block 11 and flange

12 are provided with shoulder portions, 14 and 15 respectively to receive the ends of the casing 10. Mounted on the flange 12 is a plate 16 secured to the flange by a screw 17 and adapted to be connected to any suitable holding device. Passing through the insulating block 11 are binding posts 18 and 19. Post 18 is connected with a battery 20 by a wire 21 and post 19 is connected to a lamp 22 by wire 23; the battery 20 and lamp 22 being connected by a wire 24. Secured upon the inside face of the insulating block 11 and connected with the binding post 18 is a contact spring member 25 and opposite thereto is a similar contact spring member 26 secured to the insulating block 11 by a screw 27. The contact spring members extend into the casing at a slight angle to the center thereof and are provided with depressed portions 28 and outwardly sloping ends 29 extending therefrom. A rod 30 provided on the outer end thereof with a cap 31, formed of insulating material, is designed to pass through the plate 16 and core 13 and to be held in sliding engagement therewith. The inner end of the rod is provided with a reduced portion 32 upon which is mounted an armature 34 in axial alinement with the core 13. Mounted upon the reduced portion 32 is an insulating member having a central portion 35 with a circular flange 36 engaging the armature 34 and an inwardly sloping flange 37 spaced from the flange 36. The insulating member is held in position by a nut 38 screwed upon the reduced portion 32. Positioned around the central portion 35 and between the flanges 36 and 37 of the insulating member is a circular contact member 39 having a substantially rounded or pointed periphery adapted to be normally positioned in the depressed portion 28 of the contact spring members 25 and 26 as shown in Fig. 1. A winding 40 surrounding the core 13 has one end connected with the base of the contact spring member 26 and the other end connected to the post 19 so that when the circular contact member 39 is in engagement with the contact spring members 25 and 26, current may flow through the switch from the battery 20 to the lamp 22.

Although I have shown my over-load switch in connection with a lamp circuit, it

can readily be seen that the device may be used in connection with other circuits as well.

The operation of my improved device is as follows: When the switch is in contact position as shown in Fig. 1 current from the battery 20 will pass through the wire 21, the post 18, the contact spring member 25 and the circular contact member 39 to the contact spring member 26 and thence through the winding 40 to the post 19 and through the wire 23 to the lamp 22 and back to the battery. If an overload or short circuit should exist, the excess of current will cause the winding 40 to magnetize the core 13 sufficiently to attract the armature to the core and thus pull the contact member 39 out of engagement with the contact springs 25 and 26. In this way the circuit will be broken as shown in Fig. 2 and the danger of overloading the wires be avoided. It will be seen by observing the contact spring in Fig. 2 that the outwardly sloping ends 29 thereof do not touch the contact member 39 but rest upon the edge of the sloping flange of insulating material lying against the contact member 39. By pushing the cap 31 in Fig. 2 the contact springs are forced apart until the periphery of the contact member 39 is forced into the depressed portion 28 of the springs and the circuit is restored between the battery and the lamps.

What I claim is:

1. In combination, an electric circuit, a current limiting device included therein and comprising a casing having fixed contact members formed of resilient material positioned within the casing and having outwardly sloping ends, a core of magnetic material, a rod passing through the core in sliding engagement therewith, an armature mounted on the rod and normally spaced from the core; a contact member positioned on the rod within the casing and normally engaging the resilient contact members, a magnetic coil surrounding the core and adapted to energize the same for attracting the armature to separate the contact members when the current in the circuit exceeds a predetermined value, and an insulating member carried by the rod and having a sloping face adapted to rest on the outwardly sloping ends of the resilient contact members to support the armature after the circuit is broken.

2. In combination, an electric circuit, a current limiting device included therein and comprising resilient contact members having depressed portions near their ends, an armature, a movable contact member normally engaging the resilient contact members in the depressed portions thereof, a core in proximity to the armature, a magnetic wind-

ing surrounding the core for the purpose of energizing the same to attract the armature and break the circuit when the current therein exceeds a predetermined value, and means for insulating the movable contact member from the resilient contact members, said means serving to support the armature upon the free ends of the resilient contact members when the circuit is broken.

3. In combination, an electric circuit, a current limiting device included therein comprising a casing having a core in one end thereof and fixed contact members in the other end projecting toward the core, an armature movably mounted between the core and inner ends of the fixed contact members and normally spaced from the core, a movable contact member connected with the armature normally engaging the fixed contact members and an insulating member adapted to insulate the movable contact member from the fixed contact members when current in the circuit exceeds a predetermined amount sufficient to cause the core to attract the armature.

4. In combination, an electric circuit, a current limiting device included therein comprising a casing of magnetic material having one end provided with an insulating member and the other with a head having a core thereon projecting into the casing, contact members mounted upon the insulating member extending toward the core having their free ends provided with recesses near the extremities thereof, an armature slidably mounted between the core and contact members and normally spaced from the core, a movable contact member connected with and insulated from the armature and normally engaging the first mentioned contact members within the recesses thereof, a magnetic coil surrounding the core having one end connected with said circuit independently of the first mentioned contact members and the other end connected with one of said contact members whereby when current in the circuit exceeds a predetermined amount the core will attract the armature and break the circuit.

5. In combination, an electric circuit, a current limiting device included therein comprising a casing having one end provided with an insulating member and the other with a head having a core thereon projecting into the casing, fixed contact members mounted upon the insulating member and extending into the casing in the direction of said core, an armature positioned between the core and inner ends of the fixed contact members, a movable contact member connected with the armature normally engaging the fixed contact members, a magnetic coil surrounding the core normally included in

the circuit through the movable and fixed contact members and an insulating member adapted to insulate the movable contact member from the fixed contact members 5 when current in the circuit exceeds a predetermined amount sufficient to attract said armature.

In testimony whereof I affix my signature in presence of two witnesses.

JAMES K. DELANO, Jr.
